UNITED STATES PATENT OFFICE.

JAMES MONROE HONS AND EDWARD WALLACE APLIN, OF CHICAGO, ILLINOIS,
ASSIGNORS TO GEORGE A. REES, OF CHICAGO, ILLINOIS.

OIL-INDICATOR.

1,214,788.

Specification of Letters Patent.

Patented Feb. 6, 1917.

Application filed August 26, 1914. Serial No. 858,602.

To all whom it may concern:

Be it known that we, JAMES MONROE HONS and EDWARD WALLACE APLIN, citizens of the United States, residing at Chicago, in the county of Cook and State of Illinois, have invented a certain new and useful Improvement in Oil-Indicators, of which the following is a full, clear, concise, and exact description, reference being had 10 to the accompanying drawings, forming a part of this specification.

Our invention relates to automatic controllers for internal combustion engines and has for its object the provision of an improved device of this character adapted to control or entirely stop an engine should the supply of lubricant used in the operation of the engine fail or be insufficient.

Our invention in one form contemplates 20 the provision of a device responsive to the fluid level of lubricant within the engine, which device has means should the level go below a predetermined amount to short circuit the ignition system or otherwise render 25 it inoperative, at the same time displaying a signal to the operator of the vehicle upon which the engine is located, giving him an indication as to why the engine has stopped 30 its operations.

Our invention further contemplates the provision of a plurality of devices preferably placed at the opposite extremities of the engine or crank case so that should the vehicle be ascending or descending an incline, whereby the oil may run to one extremity of the container, that the engine 35 would not thereby be stopped, it requiring the active coöperation of both devices before such a stoppage of the engine would occur.

We will explain one form which our invention may take more in detail by referring to the accompanying drawing, in which—

Figure 1 is a side view of an internal combustion engine shown as mounted in place 45 upon a vehicle; Fig. 2 is a vertical sectional view of our improved device along line 2—2 of Fig. 3; Fig. 3 is a sectional view along line 3—3 of Fig. 2; Fig. 4 is a diagrammatic view showing one form in which the circuit 50 may be arranged, Fig. 5 is an end view of another form of applying our device, and Fig. 6 is a fragmentary sectional view on line a of Fig. 5.

Referring more particularly to Fig. 1, we 55 show a vehicle body 1 as being provided with

a four cylinder engine 2 having in this instance the common crank case 3. Our engine is equipped with two of our improved devices respectively the devices 4 and 4^a. Both devices 4 and 4^a are identical in character being shown more in detail in Figs. 2 and 3. Our improved devices 4 and 4^a respectively are adapted for connection by means of pipes 38, 39 with the interior of the crank case so that oil from this crank 65 case may enter the devices 4 and 4^a respectively and will naturally have a level in each one of these devices in accordance with certain conditions to be hereinafter explained. If the engine is standing horizontal the level 70 of the oil in both devices is the same. Should however the engine be inclined to the horizontal as may be the case when the engine is going up or down a hill, then the level of the oil in one device may be below a 75 predetermined normal, and the level in the other device may be above a predetermined normal. Consequently it is readily apparent that we can avoid a false indication by requiring the conjoint control by both devices 80 before any control of the engine is effected. Should the level of the oil in both devices be below a predetermined amount, then in accordance with our invention as will presently appear, the ignition circuit of the engine is short circuited or otherwise rendered 85 inoperative, and a signal is displayed before the operator of the vehicle so that he is apprised of the reason for the stoppage of the engine.

With some forms of engine, it may not be necessary to use two devices as we may be able to utilize a single device 4^b connected by means of a single tube 6^a with the central portion of the lubricant container so that 90 this one device may serve the purposes as will be clear. This alternate form is shown by the dotted lines in Fig. 1.

Referring more particularly to Figs. 2 and 3 which set forth our device in detail, 100 we have a container tube 7 which in this instance is shown as glass, so that an inspection of the device will immediately indicate the quantity of oil within the crank case. Of course, any other suitable container may be employed naturally. The lower portion of the tube 7 is closed by the cap 8, which cap has an inlet tube 9 adapted 105 for connection with the pipe 39 leading into the crank case. The oil may thus enter 110

within the tube 7 and may pass to within a second tube 10, through the opening 11. Ports 12 and 13 are provided in the tube 10 so that the oil may readily flow around this tube for indicating purposes as already set forth. Within the tube 10 there is a float 14 so arranged that it moves up and down with the level of the oil. The opposite extremity of the tube 10 is surmounted by a ring 15 which is preferably metallic and is closed by a cap 16 provided with the binding post 17. Two contact plates respectively 18 and 19 are mounted within the lower portion of the device and insulated from each other, the contact plate 18 extending by means of the arm 20 and conductor 21 into electrical connection with the ring 15 and binding post 17. The conducting plate 19 is electrically in contact with the binding post 22. The float 14 may be of cork and it will be noted that whenever this float comes down low enough, its metallic prong or finger 23 engages the contact plates 18 and 19, and thus closes a circuit there-through which is equivalent to short circuiting the binding posts 17 and 22. Now it will be readily apparent that if the oil is low in one device, its contacts 18 and 19 will be short circuited, but if the oil is not low in the other device, its contacts will not be short circuited, and hence if both devices are in series, electrically speaking, then no control will be effected under such conditions. Both devices must be devoid of oil to effect the desired control. If one device is used, as shown in dotted lines in Fig. 1, then of course the one device may suitably control the stoppage of the engine as is readily apparent.

40 To illustrate how this control may be effected, for instance, reference will be had to Fig. 4 where our improved devices are diagrammatically indicated by their floats 14 and 14^a and their coöperating contacts 18 and 19. Spark plugs 24 are shown which control the operation of the engine and which receive their current from any well known ignition circuit, such for instance as shown, which includes the high pressure secondaries 25. A distributer 26 is also illustrated, as well as a battery 27 by which the interrupter 28 may be operated. Now whenever the circuit is closed through both contacts 18 and 19 a circuit is established 55 extending from the junction point 29 by way of conductor 30, through the two series of contacts 18 and 19 in series, conductor 31, to ground, thus grounding one terminal of the high pressure winding 25, the other 60 terminal of which is normally grounded by the conductor 32. The spark plugs 24 thus do not receive any current, being short circuited, under those conditions when both devices operate. At the same time that 65 these devices operate a circuit is established

through a lamp 33, which may be traced from the ground 34, through battery 27, lamp 33, conductor 31, to ground at 35. The operator of the vehicle is thus apprised of the reason for the stoppage of his engine. 70 Normally this lamp 33 is grounded through the coils 25, but these coils being of high resistance, do not permit enough current to pass through the lamp 33 to operate the same sufficiently to give an indication. Switch 75 elements 36 may also be included in the high resistance secondary circuits and synchronously controlled by the distributer 26. Referring more particularly to Fig. 5, we show one form in which the device may be applied to such crank cases where the splash lubricating system throws the oil level out of the horizontal so that it normally is included when the engine is running. This level is indicated by the dotted line 37. We 80 associate our improved device 4 with this container by means of two tubes respectively 38 and 39. Now whenever the oil is being agitated to assume the position shown, the oil flows into the device under pressure 85 through the tube 38. Now whenever the level of the oil gets below the orifice of the tube 38, the tendency to force oil through the tube 39 is decreased, and as the level of the oil gets lower, finally not enough oil is 90 forced through the tube 39, or may even be withdrawn therefrom by the suction of the moving oil so as to withdraw all of the oil from the device 4, thereby causing a closure 95 of the circuit to stop the engine. 100

In Fig. 6 we show more clearly the arrangement of the tubes 38, 39 with the crank case, the tube 38 being shown as having a scoop-shaped extension 40 so that the oil as it travels past is forced into the tube 38 and is 105 withdrawn by suction from the tube 39.

From what has been described it is thought the nature of our invention will be readily clear to those skilled in the art, and it will also be apparent that the device is 110 susceptible of modifications without departing from the spirit of our invention.

Having however thus described one form of our invention, what we claim as new and desire to secure by Letters Patent is: 115

1. A control system for internal combustion engines comprising an internal combustion engine having a lubricant container and an ignition circuit, and means associated with said lubricant container near the extremities thereof responsive to the lubricant level at their respective extremities to control said ignition circuit. 120

2. A control system for internal combustion engines comprising an internal 125 combustion engine having a lubricant container and an ignition circuit, and means associated with said lubricant container near the extremities thereof responsive to the lubricant level at their respective ex- 130

tremities to jointly control said ignition circuit.

3. A control system for internal combustion engines comprising an internal combustion engine having a lubricant container, float controlled means responsive to the level and velocity of flow of the lubricant to control said engine, said float controlled means having two tubes leading from different levels of said means to different levels of said container and means for causing a flow of lubricant through said tubes.

4. A device of the character described comprising an oil containing cylinder, an

internal concentric cylinder having orifices 15 in its upper and lower portions, a float in said second cylinder, and contacts in said second cylinder directly controlled by said float.

In witness whereof, we hereunto subscribe our names this 18th day of August A. D., 1914.

JAMES MONROE HONS.
